AUTOMATIC STEP-BY-STEP SWITCH

Rudolf Nebelung, Berlin-Steglitz, Germany, assignor to Siemens & Halske Aktiengesellschaft, Wernerwerk, Siemensstadt, near Berlin, Germany

Application January 2, 1931, Serial No. 506,016
In Germany May 20, 1930

6 Claims. (Cl. 179—18)

The invention relates to circuit arrangements for increasing the operating speed of stepping switches, controlled by impulses particularly in telephone systems. The object of the invention 5 consists in that a multiplication of the impulses generated in a circuit is obtained and employed for increasing the rotary speed of stepping switches. This is achieved in that each received impulse repeatedly influences the magnetic field 10 of the driving magnet.

Two embodiments showing the main features of the invention are shown in the drawing, and their operation is described below.

Fig. 1 shows one form of the invention using a 15 rotary interrupter, and Fig. 2 shows a modification of the invention using a relay interrupter for generating the impulses.

The arrangement is shown in Fig. 1 in which a 20 doubling of the rotary speed of a stepping switch is obtained in that the driving magnet of the switch has two differentially wound energizing windings D1 and D2 connected in parallel and having different numbers of ampere turns. A 25 well known form of constantly rotating interrupter RU is connected in series with the large winding. By the impulses from the interrupter RU, after the closing of the starting contact r, the movement of the stepping switch is effected.

The circuit arrangement shown in Figs. 1 and 2 30 is a diagrammatic illustration in well known form. It should be understood that the circuit arrangement may be utilized to operate any of the well known rotary line switches, finder switches or selector switches known to the telephone art. 35 For the purposes of illustration the circuit is shown applied to a rotary line switch the mechanism of which is well known, and one form of which is shown in U. S. Patent No. 1,794,888, issued March 3, 1931 to J. Erickson. The circuits herein are arranged in a form well known in the telephone art such as in Patent No. 1,855,416, issued April 26, 1932 to A. B. Pruess. In the Erickson patent above referred to the operating magnet is shown at 10. In the present arrangement the magnet having windings D1 and D2 would replace the magnet 10 of the patent and the wipers a, b, c and d correspond to wipers 4, 5, 6 and 7 of the patent.

When the interrupter just makes contact both 50 the windings conduct current, but, due to the opposing flow of the current in the two energizing windings, only one field corresponding to a single number of ampere turns is created, which attracts with a certain strength, e. g. the strength +2,

the armature of the driving magnet. If now, at a succeeding setting of the interrupter, the winding D1 with the double number of ampere turns is deenergized, a re-magnetizing of the field of the driving magnet is effected; the field is shifted from the strength +2 and an equally strong field —2 is produced in the opposite direction, which is maintained by the winding D2 with the single number of ampere turns. The result is that, at the disappearance of the field from strength +2, 10 the armature is dropped upon reaching zero, before it is again attracted by the field in the opposite direction of the strength —2. At each interruption an attraction and release of the armature of the driving magnet is effected. The 15 stepping switch thus advances two rotary steps for each received impulse.

The arrangement according to Fig. 2 shows a somewhat altered embodiment in which it is avoided that the circuit of one of the two energizing windings is permanently closed. The driving magnet also in this case has two opposing energizing windings D1 and D2 which, however, have the same ampere turns and therefore generate the same magnetic fields but in opposite 25 directions. In order to obtain an alternative and successive connecting up of the two energizing windings at each received impulse, a separate switching means is provided in the form of a changeover contact r2 in connection with the 30 relay interrupter R1 and RII which generate the impulses. When an impulse is received, the winding D1 is energized in series with relay R1, and generates, e. g. a positive field. Relay R1 closes the circuit to relay RII. Relay RII energizes and short-circuits relay R1 to cause it to release and at contact r2, winding D1 is disconnected and thus the winding D2 is connected to ground. As, however, D2 is an opposing winding, the subsequent result is the reversal of the field, up to 40 now positive, and a change thereof to the negative side. The armature of the driving magnet must, therefore, drop and is immediately attracted by the negative field, maintained by winding D2. In this case also a double stepping 45 operation is therefore obtained by the opposing energizing windings and the change of the active field of magnetic force.

As the operation of such switches is generally well known only a general description of the 50 circuit operation will be given, the above explained operation of the operating magnet having windings D1 and D2 being the new feature. A telephone subscriber's line is connected to the leads to the left of each figure and when the 55

receiver on such line is removed a circuit is completed for the line relay R over the line. Relay R energizes to close the above circuit for windings D1 and D2 at contact r, and also at its 5 other contacts closes a point in a circuit of test relay P. As is known, the intermittent operation of magnet D1—D2 causes the movement of wipers a—d over their contacts to select an idle trunk line. When such idle trunk line is reached 10 relay P energizes over a circuit including test wipers c and d to open the circuit of magnet D1—D2, to disconnect relay R, and switch the incoming leads of the subscriber's line through to wipers a and b. The operation of magnet D1—D2 to step the wipers having been explained 15 above, it is believed that this description of the general circuit operation is sufficient.

What is claimed is:

1. A circuit arrangement for increasing the 20 rotary speed of stepping switches controlled by impulses particularly in telephone systems comprising a driving magnet, means for transmitting impulses to said magnet, and means for causing each impulse received by the magnet to produce two complete operations thereof.
2. In a stepping switch, a magnet for stepping 25 said switch, means for sending impulses to said magnet, and means including two opposing windings on said magnet for causing the magnet to energize twice for each received impulse to step said switch two steps per impulse.
3. In a stepping switch, a magnet, an impulse 30 sender for sending impulses to said magnet, and means for causing each impulse to effect a double operation of said magnet, said means including two opposing windings on said magnet, the first having double the ampere turns of the second,

a permanently closed circuit for the second winding, and a circuit for the first winding including said impulse sender so that the first winding produces a magnetic field in one direction at each impulse and the second winding produces a magnetic field in the opposite direction between impulses. 5

4. In a stepping switch, a magnet having two opposite windings, a relay interrupter, an impulsive circuit including said interrupter and a changeover contact controlled by said interrupter for successively connecting said two windings to said impulsive circuit, once for each impulse, so that said magnet is operated twice for each impulse transmitted thereto. 10 15

5. A circuit arrangement for increasing the rotary speed of stepping switches controlled by impulses particularly in telephone systems comprising a driving magnet, and means for causing each received impulse to produce two complete 20 operations of the driving magnet, said means comprising two opposing energizing windings on said magnet with different numbers of amper turns, and an impulse sender connected in series with the one having the greater number of 25 ampere turns.

6. A circuit arrangement for increasing the rotary speed of stepping switches controlled by impulses particularly in telephone systems comprising a driving magnet, means for causing each 30 received impulse to produce two complete operations of the driving magnet, said means comprising two opposing energizing windings of said magnet having equal ampere turns, and a switching device alternately connecting up the 35 energizing windings to the impulse circuit.

RUDOLF NEBELUNG.

CERTIFICATE OF CORRECTION.

Patent No. 2,018,864.

October 29, 1935.

Rudolf Nebelung.

It is hereby certified that error appears in the above numbered patent requiring correction as follows: In the drawing, Figures 1 and 2 should appear as shown below instead of as in the patent:

FIG. 1

FIG. 2

and that the said Letters Patent should be read with this correction therein that the same may conform to the record of the case in the Patent Office.

Signed and sealed this 27th day of April, A. D. 1937.

Leslie Frazer
